ELECTRICAL SWITCH

Leo C. Zehnpfennig, Merkel, Tex., now by Judicial
change of name Leo C. Zee

Application March 5, 1946, Serial No. 652,163

2 Claims. (Cl. 206—54)

1

This invention relates to improvements in circuit makers and breakers and more particularly to automatic switches and the like.

One of the objects of this invention is to provide a simple, efficient and inexpensive electrical switch adapted to be associated with a door and actuated as the door moves to open or closed position.

A further object thereof is to provide an electrical switch of such a type and form that all parts thereof may be protected from accumulation of foreign matter, and be placed in such co-ordinative positions as to assure positive action at all times.

A still further object thereof is to provide an electrical gravity-operated switch with co-ordinative switch elements adapted to automatically be brought into circuit making engagement intermittently upon opening of the door, and to become automatically disengaged upon the closing of the door.

In carrying out the foregoing objects it is proposed to encase one switch element in the other in such manner that the encasing switch element may have independent movement with respect to the other element for the purpose of effectuating the disrupting of the electrical circuit which both elements close when they engage each other.

A still further object of this invention is to provide a novel construction of electrical switch characterized by allowing one switch element to have independent movement with respect to the other within prescribed limits; coupling one switch element onto the other for the purpose of closing an electrical circuit; and keeping said circuit closed for a prescribed period, determined by the requirement that the circuit be disrupted some time just prior to completely closing the door.

With the above and other objects in view my invention relates to the combination, arrangement and details of construction disclosed in the drawings and specifications and then more particularly pointed out in the appended claims.

In the drawings, wherein similar references characters designate similar parts throughout the respective views,

Figure 1 is a longitudinal sectional view of the parts of my invention.

Figure 2 is a view similar to Figure 1 but showing the parts in a circuit closing position.

Figure 3 is a front elevation, partly broken away, showing the assembly of leader and follower switch elements, and

Figure 4 is a view similar to Figure 3 but show-

ing the parts thereof in a circuit closing position.

Referring to the drawings, which are merely illustrative of my invention I disclose the parts thereof. I shall designate two specially devised switch elements as the encasing or leader switch element and the encased or follower switch element respectively. The encasing switch element is box shaped and is designated 10 having its interior 11 receiving the encased switch element which is a saddle member, designated generally 15. The latter switch element comprises a back wall 18, a top wall 17 joining the back wall, and end walls 22 which have arcuate shaped edges 16 extending from its juncture point with the outer edge of top wall 17 and with the outer edge of back wall 18, as shown in Figure 2.

For the purpose of swingably securing the outer switch member 10 to the inner switch member 15 I show the hinge pintle 12 operatively mounted at the corner of a fixed door jamb A. Secured upon the door jamb A is hinge plate 14 carrying pintle 12, while complementary hinge plate 13 is secured upon the adjacent surface of one of the walls of the encasing box switch element 10, being also mounted upon said pintle 12.

Normally, that is to say, when the door is fully closed upon the door jamb A, the encased element, having its hinged plate 14 secured to the door jamb A will have switch element or box 10 overlie or overlap the hinge plate 13, and the encasing element is completely closed around the encased element and cannot be urged in movement at all in the direction of the door jamb, only in a counter direction of movement away from the jamb A. In this way the inner open end of the box 10 is closed by the door jamb.

The arcuate edge 16 of the encased switch element 15 is concentric with hinge pintle 12, and the wall of the box switch element facing this arcuate edge of the switch element 15 is made so that when the door is moved to open position, and the box tilts under influence of gravity and moves away from the door jamb A, this particular wall will move in an arc around the arcuate edge of the encased switch element relatively thereto as is shown in Figure 2. This gives it an independent movement with relation to the movement of the encased element 15, within prescribed limits now to be explained.

Mounted upon the end walls 22 of the encased element 15 are conductor binding posts 21 which form contact members or points, which are to be placed in an electrical circuit. Lead in and lead out wires (not shown) are connected to these contact members. These contact members have

flanges 23 formed upon them. There is a connector contact member mounted on the inner side of that wall of the box switch element 10 which faces the arcuate edge 16 of the encased switch element 15. This connector member comprises a longitudinally extending plate 23a having an intermediate lug B formed with holes M in which fasteners (not shown) extend to fasten this plate upon the box wall just mentioned. The opposing ends of plate 23a are hook shaped portions 23b, which may have a springy action when flexed. Suitable insulation is operatively had between both switch elements including the insulator walls 22 through which the contact members 21 extend. Both switch elements will preferably be made from plastic material. 20 designates fasteners which secure the hinge plates upon their respective switch elements. The switch element 10 is limited in its swinging to circuit closing position by means of a pair of pins 24 carried by the outer element 10, which engage in arcuate slots 25 formed in the end walls 22 of the stationary member 15.

In operation the device functions in the following manner; when the door is open, gravity pulls one end of box 10 down, bringing connector 23a with its hooks 23b into engagement with contact members 21 of the encased switch element. Normally all parts are as shown in Figure 1. Here the box element 10 covers and encases completely the stationary switch element 15. The hook members 23b of the bridging member 23a on the box are so located, it will readily be seen from Figure 1, that they are spaced out of engagement with the contact members 21 of the stationary switch element. This bridging member 23a moves in a cycle that will contact members 23b to engage the contact members 21, as the box 10 swings by gravity around the stationary encased element 15 at the beginning of the opening movement of the door. This is the independent movement allowed the box around stationary member or element 15. This independent movement comes to an end when, in the course of opening movement of the door, the hook contact members 23b of the connector member engage the contact members 21 on the fixed stationary switch element 15, as shown in Figure 2. At this time the connector member is coupled onto the encased switch element 15.

At the moment when the hook shaped contact members 23b engaged the contact points or members 21, the electrical circuit has been closed, to an electric lamp (not shown). It is contemplated that when the door opens that the room which it closes be illuminated.

Once the contacts to the electrical lamp are included in a closed electrical circuit, the circuit will remain closed because this frictional inter-engagement between connector contacts and contact points of the respective switch elements continues during the balance of the movement of the door to open position. When the door is moved

back to closed position, in a counter direction, just prior to fully closing the door upon the jamb, the box switch element which is in tilted position on a bias with respect to the inner wall 17 of the stationary switch element, has movement around the edge 16 of the encased element. As the door moves to finally fully closed position, the box element 10 swings upwardly to the position shown in Figure 1 wherein the electrical current is broken by reason of the fact that movable contacts 23b are disengaged from stationary contacts 21. I do not mean to confine myself to the exact details of construction disclosed herein but cover all variations falling within the purview of the appended claims.

What I desire to claim is:

1. A gravity closing switch for mounting on a door frame and adapted to be moved to circuit breaking position by closing of the door; said switch comprising a stationary member formed of a horizontal top wall, a vertical front wall and opposite end walls having curved rear edges extending downwardly and forwardly, a pair of spaced contacts carried by the end walls of said member, a housing enclosing said stationary member, means hingedly securing said housing to said stationary member whereby said housing will normally swing downwardly and forwardly, and bridging contact means carried by said housing and adapted to engage said pair of contacts when said housing swings downwardly and forwardly.
2. A gravity closing switch for mounting on a door frame and adapted to be moved to circuit breaking position by closing of the door; said switch comprising a stationary member formed of a horizontal top wall, a vertical front wall and opposite end walls having curved rear edges extending downwardly and forwardly, said end walls having a pair of arcuate slots, an upwardly opening housing enclosing said stationary member, means hingedly securing said housing to said stationary member, a pair of inwardly projecting pins carried by said housing loosely engaging in said slots to limit the forward swinging of said housing, a pair of fixed contacts carried by said stationary member, a pair of hook-shaped contacts, a bridging bar fixed to said hook-shaped contacts and fixed relative to said housing whereby said latter contacts will engage said fixed contacts when said housing swings downwardly and forwardly.
